UNITED STATES PATENT OFFICE

2,083,605

WATER CLOSET

Paul E. Jertberg, Glendale, Calif.

Application July 20, 1936, Serial No. 91,483

8 Claims. (Cl. 4—254)

This invention relates generally to water closets and specifically contemplates toilet units comprising, in combination, foot rests and toilet hoppers.

5 The position of the body during the act of defecation is acknowledged to be of the greatest importance for most efficient extrusion of indigestible waste matter. It is generally concurred that the passages of fecal matter through the 10 lower regions of the alimentary canal is resisted by a series of antiperistaltic waves which are offset during actual defecation by the voluntary contraction of the abdominal muscles. A supported elevation of the legs tends to reduce the 15 sacculations of the lower intestine and relieves strain on the abdominal muscles by other parts of the body which accordingly obviates dissipation of their contractive energy.

It is a general object of the present invention 20 to provide a toilet assembly embodying in combination a water closet and foot rest adaptable for operative unity in supporting the body of a user in a position most conducive to effective elimination.

25 Another object is to provide a device comprising a water closet and foot rest adapted for conjunctive use, having a handle by which the foot rest may be manually adjusted and locked at any desired vertical position to accommodate individuals of various heights.

30 Another object is the provision of mechanism for elevating the foot rest which is simple and inexpensive to manufacture yet durable in use.

Other objects and salient features of my invention such for example as facility of operation, 35 speed and convenience of adjustment, and neatness of appearance, will be obvious to those of skill in the art upon an examination of the following description read in the light of the accompanying drawing, in which,

40 Fig. 1 is a perspective view of my invention;

Fig. 2 is a sectional view of the adjustable foot rest;

45 Figs. 3 and 4 are sections taken on correspondingly-numbered lines of Fig. 2;

Fig. 5 is a perspective view of the elevator block employed in the embodiment illustrated for raising the foot rest to any adjusted position.

Referring to the drawing in detail, the numerals of which indicate similar parts throughout the several views, 6 designates generally a conventional type wall closet secured by any well known means to a wall 7 comprising a bowl 8 and seat 9. A foot rest 10, about to be described in detail, is removably disposed on the floor 11 in front of the closet 6, it being understood that the foot rest may be attached to the floor or integrally formed with the closet to maintain their most desirable relationship. The foot rest 10 embodies a base 12 having perpendicular end

walls 13 and side walls 14. A rod 15 extends through the base 12 in approximately its center and is secured parallel to walls 13 and 14 by a flanged nut 16 threaded thereto which is secured to the underside of the base by screws. An inverted box 17 telescoped over the walls 13 and 14 comprises a foot plate 18, declining to or from the direction of the closet 6, as desired, and vertical walls 19 and 20 adapted to slidably engage walls 13 and 14, respectively.

10 A sub-plate 21 within box 17 is perpendicularly secured to the walls thereof below the foot plate 18. Holes 22 and 23 are centrally disposed in plate 18 and sub-plate 21, respectively, so as to be in concentric alignment with rod 15. A liner 24 secured to the upper side of sub-plate 21 by a flange bracket 25 extends upwardly through hole 22. A pair of diametrically-opposite holes 26—26 in the upper end of liner 24 are provided for a purpose hereinafter described.

20 At each end of the inclosure formed by walls 13 and 14 an elevator block 27 is slidably supported on base 12, each block comprising a pair of sliding members 28 spaced apart in parallel alignment, with their sides engaging said walls 14, by bars 29. The upper edge of each member 28 of respective elevator blocks 27 is inclined to a peak and recedes on the opposite side adjacent the end walls 13 to provide inner and outer bearing surfaces 30 and 31, respectively, oppositely inclined on each member. Box 17 is supported inclined on each member. Box 17 is supported above base 12 by means of a series of projections 32 rigidly attached, by any well known means, to respective corners of the under-side of sub-plate 21 and spaced from walls 19 and 20 a distance substantially equal to the width of walls 13 and 14. Each projection is provided with a downwardly-directed angular face 33 parallel to the bearing surface 31 therebelow with which it is adapted to operatively engage.

35 The weight of box 17, transmitted to the end faces 33 of projections 32 normally tends to displace blocks 27, moving them inwardly. Movement of the blocks in the opposite direction toward the end walls 13, conversely displaces the 40 projections 32 which elevates the box and foot plate 18.

The apparatus for compelling separation of the blocks and the vertical movement of the foot plate 18 includes a tube 34 which telescopes over rod 15 and extends upwardly through liner 24. On the lower end of tube 34 a separator plate 35 is rotatably secured by any means well known in the art having opposite lower edges 36 rounded and adapted to normally contact the upper extremity of each of the inner bearing surfaces 30 of blocks 27 when the blocks are relatively adjacent at the middle of the base. Handle 37 connected by a collar 38 to the upper end of tube 34 enables manual manipulation of the tube 45

in a manner about to be described. By exerting pressure on the handle 37, the plate 35 will be moved toward the base, causing the respective edges 36 to bear against the inclined bearing surfaces 30 of the elevator blocks 27 which separates the blocks and in turn elevates the foot plate 18 in the manner above described.

To maintain parallel alignment of the lower edges 36 of the separator plate 35 with the bearing surfaces 31 of the elevator blocks a pair of vertical guide rods 39 are bolted or otherwise secured to base 12 and extend upwardly through holes 40 and plate 35. Nuts 41 are threaded to the upper end of each of said rods to limit upward movement of the separator plate and tube 34, and accordingly determine the lowest position of the foot plate 18.

To accommodate individual comfort of a user of the foot rest, as well as to compensate for various heights of users, I provide locking mechanism by which the foot plate may be fixed at any desired position of its vertical movement. Tube 34 has a pair of longitudinal diametrically-opposite slots 42 cut therein of a length substantially 25 equal to the distance between the limits of vertical movement of plate 35. A pin 43 projecting into the liner 24 through one of holes 26 extends through the slots and is secured in the other of holes 26 of the liner. A series of recesses 44 are 30 cut in the edge of respective slots 42 on opposite sides of pin 43. With tube 34 in the vertical adjusted position desired, rotation of the tube will move the side of the recesses 44, which are horizontally aligned with the pin, into engagement 35 therewith and simultaneously move the slots 42 out of vertical alignment with pin 43 to lock the tube, separator plate, and foot plate vertically immovable. Reverse motion of the tube will return the slots 42 to alignment with pin 43 and 40 again permit longitudinal movement of the foot plate in an obvious manner.

It will be understood that numerous changes may be incorporated in the embodiment of my invention disclosed, as, for example, a horizontally reciprocable separator plate may be substituted for the vertically movable plate described, a friction lock of any type well known in the art may be employed to maintain adjusted position of the foot rest, and details of construction with reference to relative proportion, design, size, and arrangement of the many parts may be varied without departing from the spirit of my invention as defined in the appended claims.

55 What I claim and desire to secure by Letters Patent is:

1. In a device of the character described, a closet bowl, a foot rest comprising a base, an elevator block slidable laterally on said base, an inclined foot plate having projections on its underside supported by said elevator block, means to compel lateral movement of said block to displace said projections and foot plate upwardly, and means to support said foot rest in front of said bowl.

60 2. In a device of the character described, a foot rest comprising a base, a pair of elevator blocks slidably supported on said base, each of said blocks having inclined upper faces, an inclined foot plate slidably supported on said elevator blocks by a plurality of projections attached thereto, each of said projections having an inclined face parallel to and bearing upon the outer inclined faces of respective blocks, and a

separator member to impel relative separating movement of said blocks to displace said projections and foot plate upwardly.

3. In a device of the character described, a base, vertical walls bordering said base, an inverted box comprising an inclined foot plate and downwardly extending walls telescoping the vertical walls of said base, a pair of elevator blocks slidably maintained on said base by said vertical walls, each carrying inclined upper faces on opposite sides thereof, projections depending from the underside of said foot plate adapted to contact the outer inclined faces of each of said blocks, a vertically movable separator member between said blocks adapted to bear on the inner inclined faces of said blocks, and a handle above said foot plate connected to said separator member by means extending through said foot plate, to control vertical movement of said separator member.

4. In a device of the character described, a base, vertical walls bordering said base, an inverted box comprising an inclined foot plate and downwardly extending walls telescoping the vertical walls of said base, a pair of elevator blocks slidably maintained on said base by said vertical walls, each carrying inclined upper faces on opposite sides thereof, projections depending from the underside of said foot plate adapted to contact the outer inclined faces of each of said blocks, a vertically movable separator member between said blocks adapted to bear on the inner inclined faces of said blocks, a tube rotatably connected to said separator member and extending through said foot plate, said tube having a slot longitudinally disposed therein, said tube also having a series of recesses therein laterally extending from said slot, and a pin connected to said foot plate slidable in said slot upon relative movement of said foot plate and tube, being adapted to be received in any of said recesses upon rotation of the tube to maintain said foot plate and tube in vertically immovable relation.

5. In a device of the character described, a foot rest comprising a base, an elevator block slidable laterally on said base, an inclined foot plate having projections on its underside supported by said elevator block, and means to compel lateral movement of said block to displace said projections upwardly.

6. In a device of the character described, a base, an inclined foot plate above said base to limit the direction of movement of said foot plate with respect to said base, mechanism to move said foot plate vertically within the limits fixed by said guides, a handle connected to said mechanism to actuate the same by vertical movement thereof.

7. In a device of the character described, a base, a foot plate, means to limit said foot plate to vertical movement with respect to said base, and means including a handle to move said foot plate in a vertical direction by movement of the handle in an opposite direction.

8. In a device of the character described, a base, a foot plate, means to limit said foot plate to vertical movement with respect to said base, means including a handle to move said foot plate in a vertical direction by movement of the handle in an opposite direction, and means to releasably retain said foot plate in any vertically adjusted position.
